GAS FUELED SINGEING BURNER

Hartwig Millard Hanson and Edward J. Funk, Jr.,
Baltimore, Md., assignors to The C. M. Kemp
Manufacturing Company, Baltimore, Md., a
corporation of Maryland

Application June 14, 1950, Serial No. 168,096

6 Claims. (Cl. 158—105)

1

This invention relates to a radiant heat flame compression burner for singeing textiles. Textiles have previously been singed very effectively according to the apparatus disclosed in Patent No. 2,410,542. It has been found that certain modifications in the burner there illustrated permit the omission of the cumbersome water cooling provisions previously found necessary in the flame compression type burner. Water cooling is especially uneconomical since a primary object is to maintain a very hot flame, while water-cooled edges or guides tend to cool the flame and waste heat.

The fabric in this invention may be drawn across the burner in either direction and in contact with metallic guides which are kept adequately cooled by air. The guides are spaced on either side from the burner orifices by a pair of beds having refractory surfaces. From the burner orifices a flame from a perfectly proportioned fuel and air mixture plays on the fabric and is deflected by the fabric in both directions over the refractory surfaces. These surfaces are inclined in opposite directions from the burner orifices toward the fabric forming therewith a pair of wedge-shaped areas. The pressure of the flame causes the hot gases to flow in both directions from the orifices toward the small ends of the wedges, the decreasing area causing a rubbing effect as the gases are further compressed or confined by the fabric, this is especially true on the burner side leading from the center, in the direction of fabric web travel. The fabric, therefore, forms one side of a large combustion chamber solidly filled with flame under pressure.

The combustion chamber contains no oxygen—the nap is not burned but is carbonized by the high temperature flame and the resulting carbon is blown away by the combustion gases as they escape at the side edges of the fabric. It is the high temperature of the flame compressed between the fabric and the refractory surfaces which is so effective in singeing and the compression is greater because of the wedge shape of the areas between the refractory bed and the fabric. The metallic supports for the refractory beds are channelled to minimize the contact of the metal, and to permit air to circulate, to dissipate the heat in the beds and supports. Two burners are generally used on any singeing machine, one burner for each side of the fabric.

Other objects and advantages of the invention will be apparent from the following description and the accompanying drawings forming a part hereof and in which:

2

Figure 1 is a front elevational view of the burner.

Figure 2 is an end elevational view thereof.

Figure 3 is a partial plan view, partly with the burner bed removed.

Figure 4 is a partial longitudinal sectional view taken along the line 4—4 of Figure 2.

Figure 5 is an enlarged fragmentary top plan view of the orifice plate and holder.

Figure 6 is a fragmentary sectional view taken along the line 6—6 of Figure 5.

Figure 7 is a transverse sectional view taken along the line 7—7 of Figure 1.

Figure 8 is a transverse sectional view taken along the line 8—8 of Figure 3.

In the drawings similar numerals refer to similar parts in the several views.

The burner beds are made up of refractory material such as fire bricks 1 and 2 which are preferably trapezoidal in shape as best seen in Figure 7. These are held between the central burner body or body member 3 and the acute angled guide brackets 4 and 5 having ribs 4' and 5'. By virtue of the trapezoidal shape of the bricks and the acute angle in brackets 4 and 5, the bricks 1 and 2 are wedged in place firmly. The end bars 6 and 7 close the longitudinal ends of the burner between brackets 4 and 5.

It will be observed that the inner end walls 3 and 9 of bricks 1 and 2 rest against substantially vertical and parallel outer body walls 10 and 11 so that the upper refractory surfaces 12 and 13 of the bricks are inclined upwardly away from the body 3.

The top walls 14 and 15 of the body, Figure 8, are substantially at right angles to the outer walls 10 and 11 and receive thereon the orifice plate 16 which is held down by means of rectangularly recessed combustion chamber members or holders 17 fastened by means of screws 18 to the body. A completely combustible mixture of fuel and air is fed to orifices 19 in the orifice plate 16 through fuel chamber 20 and intermediate chambers 21 and 21'. After striking the cloth the flame travels parallel with it in opposite directions and is compressed between the cloth and the refractory surfaces, being forced into the pair of wedge-shaped areas by virtue of the positive and constant pressure under which the gas-air mixture is delivered to the combustion chamber, also the travel of the web toward the wedge area, in the direction of travel, carries the flame along, and wedges it yet more against the fabric.

The lower portion 22 of the body 3 is inclined to the outer walls 10 and 11 and has a semi-cir-

cular bottom wall 23 with inclined parallel side walls 24 and 25, Figure 8. The right side wall of the upper body angles back to form a baffle 26. The lower body chamber 20 receives a completely combustible mixture of air and fuel from both ends through pipes 21, as shown in Figure 1. The semi-circular bottom wall has a plurality of valves 28 angularly mounted therein at each end of the burner which, when open, admit the combustible mixture to intermediate chambers 21'. These chambers are separated by partitions 33 which permit the use of the burner for wide or narrower webs, depending upon the opening of the valves 28. These valves close openings 29, Figure 7, in the partition 30 between the fuel chamber 20 and intermediate chambers 21'. As shown there are six of these valves. The partition 30 extends at right angles to the inclined side walls 24 and 25 with baffle 26 opposite opening 29.

The combustion mixture is fed under pressure through openings 29, and as it comes through at right angles to the partition 30, the mixture strikes the baffle 26 opposite thereto of intermediate chambers 21' and flattens out, spreading with equal pressure throughout the compartment of each of the chambers 21', so that pressure on the plate 16 is even, for all the orifices thereof.

Between the most central partitions 33 of the burner are smaller openings 31 closely spaced along the length of the central section of the partition 30. As shown in Figure 8 these openings are located at the uppermost portion of the partition at the juncture thereof with the inclined side wall 24 and are drilled at the maximum possible angle to the orifice plate 16. The combustion mixture is thus directed to the right and not parallel to the orifices in the plate 16. It has been found in practice that this arrangement effectively prevents blowing of the mixture through the orifices.

As seen in Figure 7, the brackets 4 and 5 are fastened to the body through flanges 32 thereof by means of bolts 33. The brackets have grooves or channels 34 cut therein to reduce contact of the brackets with the bricks 1 and 2. This reduction of contact minimizes heat transfer between the brackets and bricks to aid in maintaining the brackets at a sufficiently low temperature to preclude injury to the cloth and to aid in maintaining the heat of the bricks. The lugs 35 of the burner body to which flanges 32 are bolted are spaced and cut down the heat transfer to the burner and prevent warping thereof, as do grooves 34' in the burner body, and also ribs 4' and 5' prevent warping of the supports 4 and 5.

The fabric indicated by reference numeral 36 rides on the rounded edges or supports 37 of the brackets 4 and 5 projecting above the surfaces 12 and 13 of the bricks. The flame is completely cut off from following the cloth by these projecting edges 37. The forward edge which is contacted second by the fabric web may be said to wipe the flame from the cloth. It will be apparent that the cloth may travel in either direction transversely across the burner.

It will be seen that the burner of this invention holds the fabric the required distance from the beds by means of smooth machined edges which will not snag the cloth. A close regulation of the flame is permitted by the valves admitting the combustible mixture to the burner so that control of the extent of the singeing operation is always obtainable.

What is claimed as new and is desired to be secured by Letters Patent is:

1. A burner to singe a fabric web drawn thereover comprising an elongated metallic air cooled burner having a burning face, a central body member, an elongated burner orifice plate spaced inwardly in the body member from the face, metallic supports on the body member spaced laterally and outwardly from the orifice plate and parallel thereto on each side thereof, the supports having outer edges lying in a plane parallel to the orifice plate and spaced outwardly from the burning face, refractory beds forming the burning face and supported by and between the body member and the metallic supports, the beds at their outer edges adjacent the supports being spaced inwardly from the plane through the said edges of the metallic supports, and then sloping straight inwardly toward the body member forming a broad V-shaped combustion area bounded at its outer sides by said metallic supports, the supports together forming a clamp to hold the beds in the burner and against the body member, and means to supply a completely combustible mixture to the orifices of said orifice plate, the burner and beds being adapted to have a fabric web drawn transversely thereover, forming therebetween a substantially closed combustion singeing chamber, the flame from the burner being spread to both sides of the burner, the supports being adapted by contact therewith to space the web from the beds and to confine the flame between the supports, the sloping bed last opposite a passing web squeezing the flame closely against the web and the adjacent metallic support edge wiping the flame from the web.

2. The burner of claim 1 including a plurality of substantially spaced lugs extending from each side of the body member to the metallic supports and to which the supports are connected, the lugs being spaced from the refractory beds, whereby air may circulate between the beds and lugs.

3. The burner of claim 1 including a plurality of ribs extending longitudinally of each metallic support, between the support and the refractory beds, to support the beds on the ribs and space the beds from the supports.

4. A burner to singe a fabric web drawn thereover comprising an elongated burner having a burner body, a burning face thereon, an elongated burner orifice plate on the burner body spaced inwardly from and longitudinally centrally in the burning face, metallic supports on the burner body spaced laterally and outwardly from the orifice plate and parallel thereto on each side thereof, the supports having edges lying in a plane parallel to the orifice plate and spaced from the burner body, outwardly from the burning face, refractory beds forming the burning face and supported by and between the burner body and metallic supports, the burner body having therein a fuel chamber and a chamber intermediate between the fuel chamber and the orifice plate, the body forming walls for said chambers, a partition angularly disposed with respect to said plate, between the fuel and intermediate chambers, having laterally directed orifices therein, valves in said orifices to control the flow of fuel therethrough, one wall of said intermediate chamber extending in front of the orifices in said partition, constituting a longitudinally extending baffle to break the direct flow of fuel from the valves to the orifice plate.

5. The burner of claim 4 in which the beds are spaced inwardly from the plane through the

edges of the metallic supports and form a combustion area bounded at its outer sides by said metallic supports, the supports together forming a clamp to hold the beds in the burner and against the burner body.

6. A flame compression burner adapted to have a fabric to be singed passed thereover comprising an elongated burner having a burner body, a burning face thereon, an elongated burner orifice plate on the burner body spaced inwardly from the burning face, a pair of beds having surfaces of refractory material forming the burning face, one on each side of said plate, and sloping in opposite directions outwardly in V-formation from the plate, the burner body having therein a fuel chamber and a chamber intermediate between the fuel chamber and the orifice plate, the body forming walls for said chambers, a partition angularly disposed with respect to said plate, between the fuel and intermediate chambers, hav- 15 20

ing laterally directed orifices therein, valves in said orifices to control the flow of fuel therethrough, one wall of said intermediate chamber extending in front of the orifices in said partition constituting a longitudinally extending baffle to break the direct flow of fuel from the valves to the orifice plate.
